UNITED STATES PATENT OFFICE

FRANK H. PRESCOTT, OF ANDERSON, INDIANA, ASSIGNOR TO DELCO-REMY CORPORATION, OF ANDERSON, INDIANA, A CORPORATION OF DELAWARE

ENGINE-STARTING APPARATUS

Application filed January 17, 1929. Serial No. 333,139.

This invention relates to apparatus for starting internal combustion engines, and one of the objects of the invention is to provide simple and durable mechanism for manually moving the gear which is operated by the starting motor into mesh with a gear connected with the engine to be started, and thereafter for causing the motor to operate to crank the engine.

More particularly, it is an aim of the present invention to provide a simple and durable mechanism for manually causing the starting motor gear to be rotated prior to meshing with the engine gear, in case a gear tooth abutment occurs before meshing takes place. This aim of the present invention is accomplished by employing a pinion shifter which moves endwise along the axis of the pinion and which cooperates with means causing the shifter to rotate as it moves endwise. Motion is transmitted from the shifter to the pinion both axially and rotatively by a spring located between the shifter and the pinion, the spring being preferably a helical coil spring arranged coaxially with respect to the pinion and shifter. In case the pinion teeth abut the engine gear teeth before meshing takes place, the spring will yield to permit endwise movement of the shifter while endwise movement of the pinion is being arrested by reason of the gear tooth abutment. While the shifter moves endwise, it is caused to rotate and the spring transmits this rotary movement from the shifter to the pinion in order to cause the pinion to be rotated into meshing registration with the engine gear while this spring yieldingly presses the pinion against the engine gear.

Further objects and advantages of the present invention will be apparent from the following description, reference being had to the accompanying drawings, wherein a preferred form of the embodiment of the present invention is clearly shown.

45 In the drawings:

Fig. 1 is a fragmentary, side view, partly in section, of the engine starting apparatus embodying the present invention.

Fig. 2 is a sectional view on the line 2—2 of Fig. 1.

Fig. 3 is a sectional view on the line 3—3 of Fig. 1.

Fig. 4 is a sectional view on the line 4—4 of Fig. 1.

Fig. 5 is a vertical, longitudinal, sectional view of a part of the apparatus, this section being taken on the line 5—5 of Fig. 3.

Fig. 6 is a plan view of a sheet metal blank of which a portion of the apparatus is formed.

Fig. 7 is a side view of a portion of the engine starting apparatus, showing the condition of the engine starter drive just prior to meshing the motor pinion with the engine gear.

Fig. 8 is a sectional view on the line 8—8 of Fig. 7.

Fig. 9 is a view of the apparatus looking in the direction of arrow 9 of Fig. 7.

Fig. 10 is a view similar to Fig. 7, showing the condition of the starting apparatus just prior to cranking the engine.

Fig. 11 is a view similar to Fig. 10, showing the condition of the apparatus while cranking the engine.

Fig. 12 is a view similar to Fig. 11, showing the condition of the apparatus after the engine starts and before the operator releases the pedal or actuator.

Fig. 13 is a plan view of a sheet metal blank of which a portion of the starting apparatus is formed.

Fig. 14 is a side view of a washer used as a stop collar on the motor shaft, Fig. 14 being drawn to twice the scale of the other figures.

Fig. 15 is a sectional view on the line 15—15 of Fig. 14.

Referring first to Figs. 1 to 6 of the drawings, 20 designates a frame or bracket for attaching the starting motor to the frame of the engine to be started, and part 20 provides the housing for the starting gearing. The gear housing 20 supports a starting motor field frame 21 supporting at its left hand end (not shown) a bearing (not shown) for supporting an armature shaft 22 having at its right end a journal 23 received by a bearing 24 provided by the housing 20. The frame 20 provides a finished surface 25 for receiving a thrust washer 26 cooperating with a shoulder 27 provided by the shaft 22 in order that the

frame 20 may receive the thrust of the shaft while the engine is being cranked.

Shaft 22 supports a pinion 30 which is movable endwise along the shaft toward the right into mesh with a gear 31 connected with the engine to be started, this gear being preferably a gear provided by the flywheel of the engine. The pinion 30 is driven by the shaft 22 through a lost motion helical splined driving connection. This connection is provided by helical shaft splines 32 which cooperate with internal helical splines provided by the pinion 30. As shown more particularly in Fig. 4, the helical grooves 34 in the hub of the pinion 30 are greater in width than the shaft splines 32 so that there will be lost motion, rotatively, between the shaft 22 and the pinion 30. This is desirable in order that the pinion may be rotated manually without rotating the shaft 22.

The pinion 30 is moved manually endwise into mesh with the engine gear 31 and is manually rotated, in case of gear tooth abutment, by manually operated pinion shifter 36 designated in its entirety by numeral 36 and comprising a disc 37 attached to a tubular hub 38. The hub 38 is constructed by forming into a cylinder, a sheet metal blank 39 shown in Fig. 6. This blank is provided with dovetail tangs 40 for interlocking with dovetail tangs 41 separated by notches 42 which receive the tangs 40 when the blank 39 has been formed into a cylinder. The blank 39 is provided with slots 43 which, after the blank has been formed into the tube, will be oblique to the axis of the tube and will be diametrically opposite. Adjacent the edge surface 45, the blank 39 is provided with lugs 46 which are formed by partly punching out the metal of the blank as shown more particularly in Fig. 5. After the blank 39 has been formed into the tubular hub 38, the disc 37 is placed upon the hub 38 and is shoved against the stop lugs 46. Then the left hand of the tube 38 is swaged or spun over against the disc 37 as indicated at 47 in order to securely attach the disc 37 to the hub 38 and so that rotation may be transmitted from the hub 38 to the disc 37.

The oblique slots 43 in the hub 38 receive opposite ends of a pin 50 extending diametrically through the shaft 22. The pin and oblique slot connections between the shifter hub 38 and the shaft 22 provide means for causing the pinion shifter to rotate while it is being moved endwise. Motion is transmitted from the shifter 36 to the pinion 30 by a helical coil spring 51 having one end attached to the disc 37 as indicated by numeral 52 and having the other end 53 formed parallel to the axis of the spring and extending into a hole 54 provided in one of the teeth of the pinion 30. The turn 55 of the spring 51, from which the spring end 53 directly extends, is located substantially in a plane at

right angles to the axis of the spring. This turn 55 is located between the left end faces of the pinion teeth and a washer 56, which is retained upon the hub 57 of the pinion 30, by a wire split ring 58 received by a suitable annular groove provided by the hub 57. The washer 56 is provided with a notch 59 for receiving a portion 60 of the spring 51 which connects the flat turn 55 with the helical turn next adjacent to it. It is therefore apparent that the spring 51 is capable of transmitting motion both axially and rotatively from the shifter 36 to the pinion 30.

The shifter 36 is operated by manually operable mechanism including an actuator or lever 70 attached to a hub 71 rotatably supported by a stud 72 carried by the housing 20. The lever 70 is yieldingly maintained in normal position, shown in Fig. 1, by a spring 73 having an intermediate portion coiled around the stud 72, having one end 74 bearing against the frame 20 and the other end 75 bearing against the lever 70. The spring 73 is biased for urging the lever 70 in a clockwise direction as viewed in Fig. 1. The lever 70 supports a stud 76 arranged to engage the plunger 77 of an electric switch housed within a case 78 attached to the motor field frame 21. This switch when closed will connect the electric motor circuit with a current source.

The actuator or lever 70 is connected by disconnectible means with pinion shifter 36. This disconnectible means includes a stud 80 attached to the lever 70 adjacent its lower end and normally received within the notched portion 81 of a triangular shaped opening 82 provided by a sleeve 83. Referring to Fig. 13, the sleeve 83 is constructed by forming into tubular shape the sheet metal blank 84 shown in Fig. 13. The blank 84 is provided with dovetail tangs 85 which cooperate with dovetail tangs 86 spaced by notches 87 which receive the similarly spaced tangs 85. In this way the abutting edges of the blank adjacent the seam extending longitudinally of the tubular sleeve are locked together. The blank 84 is provided with tangs 88 which, after the blank has been formed into a tube, are received by suitable notches formed adjacent the periphery of a disc 89, supported by tubular hub 90 which slides along the shaft 22. The sleeve 83 is supported between its ends by a disc 91 through which the hub 90 extends. The disc 91 bears against stop lugs 92 provided by the hub 90 and the right end of the hub 90 is swaged or spun over against the right hand side of the disc 91 as indicated by numeral 93. The left end of the hub 90 is spun over against the left sides of the disc 89 as indicated by numeral 94. The spinning over of the hub 90 against the disc 89 causes the disc 89 to be forced against the left end of the sleeve 83 and hence tends to move the sleeve 83 toward the right relative to the disc 91. However, this motion

cannot take place due to the fact that the sleeve 83 is provided with stop lugs 95 which bear against the left side surface of the disc 91 as shown in Fig. 11. The sleeve 83 is provided also with an opening 96 defined by a surface 97 which receives a lug 98 extending from the disc 91 into the opening 96.

The operation of the invention is as follows:

- 10 To start the engine the operator moves the lever 70 in a counterclockwise direction thereby causing the stud 80 to move along the shaft 22 toward the right until it engages an edge surface 100 which in part defines the notch 81. Then the sleeve 83 will move toward the right carrying with it the hub 90 which engages the shifter hub 38 causing it to move toward the right also. Motion is transmitted from the shifter hub 38 through the spring 20 51 to the pinion 30 causing the latter to move endwise toward the right into engagement with the engine gear 31. In case of gear tooth abutment arresting further motion of the pinion 30, continued counterclockwise movement of the lever 70 will cause the pinion shifter 38 to move toward the right and to rotate relative to the shaft 22 on account of the pin and oblique slot connection between the pinion shifter hub 38 and the shaft 22. 25 The rotary movement of the hub 38 is transmitted to the pinion 30 through the spring 51 causing the pinion 30 to rotate while it is being yieldingly pressed against the abutting teeth of the engine gear 31. Figs. 7, 8 30 and 9 show the condition of the starting apparatus after the pinion has been rotated into mesh with the engine gear 31 and just before meshing has taken place. It will be noted that the pinion has been rotated from the 35 position shown in Fig. 4 to the position shown in Fig. 8 and that its splines 33 have been rotated from the demeshing side of the shaft splines 32 toward the driving sides of the shaft splines 32. There is sufficient lost motion between the shaft splines 32 and the pinion splines 33 to permit rotating the pinion through an angle substantially equal to one-half the angle between the pinion teeth before the lost motion is taken up.
- 40 At the instant the pinion has been manually rotated into meshing registration with the engine gear, it will be assisted into mesh with the engine gear by the spring 51 which has been somewhat compressed during the 45 movement of the shifter 38 endwise while the pinion 30 remains stationary. Before the lever 70 has been moved sufficiently to cause the motor switch to be closed by the cooperation of the stud 76 of the lever 70 with the 50 switch plunger 77, the pinion 30 will have been moved nearly into full mesh with the engine gear 31 as shown in Fig. 10. The closing of the motor switch will cause the shaft 22 to rotate. This rotation of the 55 shaft 22 causes the pinion 30 to be moved a

slight distance against a stop washer 110 having a plane portion 111 surrounding the shaft 22 and having suitable notches 112 for receiving the shaft splines 32. The washer 110 abuts a wire split ring 113 received by a suitable interrupted annular groove provided by the spline 32. The washer 110 includes a cylindrical portion 114 which encloses the wire split ring 113 and which is provided with tangs 115 which may be bent around the wire ring 113 in order to prevent movement of the ring 113 out of the grooves provided by the shaft splines 32. Thus, while the engine is being cranked, thrust of the pinion toward the right is transmitted to the shaft 22 by the washer 110 and wire split ring 113. As explained before, the end thrust of the shaft is transmitted to the frame 20 through the thrust washer 26. During the cranking of the engine, the apparatus is in the condition shown in Fig. 11. Comparing Fig. 11 with Fig. 10, it will be noted that the sleeve 83 has become separated from the pinion 30 and that the actuator or lever 70 has been disconnected from the sleeve 83. This movement of the sleeve 83 takes place due to the fact that when the shaft 22 rotates in the direction of the arrow 120 in Fig. 11 while cranking the engine, the sleeve 83 is frictionally dragged by the shaft 22 in the same direction. This rotation of the sleeve 83 causes the notch 81 to move away from the stud 80 and the oblique surface 121 which in part defines the triangular aperture 82, to engage the stud 80. Since the stud 80 remains stationary while the sleeve 83 is being rotated by the shaft 22 in the direction of the arrow 120 in Fig. 11, the sleeve 83 will be moved toward the left from the position shown in Fig. 10 to that shown in Fig. 11. In this way the sleeve hub 90 is separated from the shifter hub 38 so that, although the lever 70 may remain in the position shown in Fig. 11, the pinion 30 may be automatically demeshed from the engine gear when the engine starts. As soon as the engine becomes self-operative, the pinion 30, the spring 51 and the shifter 38 move from the position shown in Fig. 11 to the normal position shown in Fig. 12, although the operator has not yet released the lever 70. When the lever 70 is released, the spring 73 will return the lever 70 to normal position. During the return of the lever to normal position, the lever stud 80 engages cammingly the oblique surface 121 provided by the sleeve 83 and causes the sleeve 83 to return to normal position shown in Fig. 1. The switch plunger 77 returns to switch open position by a spring 122.

The spring 51 operates also to prevent accidental movement of the pinion 30 into mesh with the engine gear. The spring 51 is normally biased so as to urge the pinion 30 in the direction of the arrow 125 in Fig. 5 or 126 in Fig. 4. In other words, the spring 51

urges the pinion splines 33 against the demeshed side of the shaft splines 32 with a pressure sufficient to produce a substantial amount of friction between the pinion splines and shaft splines so that the pinion 30 tends to remain normally separated from the flywheel gear 31. The spring 51, being biased for urging the pinion 30 in the direction of arrow 125, is biased for urging the shifter sleeve 38 in the opposite direction as indicated by arrow 126. Normally, the ends of pin 50 are received by notched portion 43 extending from the notches 43 in a direction which is different from the manner in which the major portion of the slots 43 extends. It is therefore apparent that before the pin 50 can be received by the major portion of the slots 43, the shifter hub 38 must move relative to the pin in a direction opposite to that in which it is urged by the spring 51. Consequently when the starting apparatus is subjected to vibration which would tend to move the pinion 30 endwise, the shifter hub is yieldingly latched to the shaft 22 by reason of the cooperation between the pins 50 and the notched extensions 43 of the slot 43.

While the form of embodiment of the present invention as hereinafter disclosed, constitutes a preferred form, it is to be understood that other forms might be adopted, all coming within the scope of the claims which follow.

What is claimed is as follows:

1. Engine starting apparatus comprising, in combination, a motor; means for connecting the motor with a gear of an engine to be started and including a shaft, a pinion movable axially along the shaft into mesh with the engine gear, and a lost motion driving connection between the shaft and pinion; a pinion shifter movable axially of the shaft; means for effecting rotation of the shifter while it is moved axially; a spring for transmitting axial and rotary movement from the shifter to the pinion whereby the pinion may be rotated in case it abuts the engine gear prior to meshing, said pinion being yieldingly urged by said spring against the engine gear; and means for operating the shifter.

2. Engine starting apparatus comprising, in combination, a drive shaft; a pinion shiftable axially of the shaft, and connected thereto by a lost motion connection; a shifter movable along the shaft and having connection therewith such that axial movement of the shifter is accompanied by rotary movement; a spring for transmitting axial and rotary movement from the shifter to the pinion whereby the pinion may be rotated in case it abuts the engine gear prior to meshing, said pinion being yieldingly urged by said spring against the engine gear; and means for operating the shifter.

3. Engine starting apparatus comprising, in combination, a motor; means for connecting the motor with a gear of an engine to be

started and including a shaft, a pinion movable axially along the shaft into mesh with the engine gear, provisions whereby the pinion will be automatically demeshed from the engine gear when the engine starts, and a lost motion driving connection between the shaft and pinion; a pinion shifter movable axially of the shaft; means for effecting rotation of the shifter while it is moved axially; a spring for transmitting axial and rotary movement from the shifter to the pinion whereby the pinion may be rotated in case it abuts the engine gear prior to meshing, said pinion being yieldingly urged by said spring against the engine gear; a manually operable actuator for moving the shifter; and means for automatically disconnecting the actuator from the shifter before the engine starts.

4. Engine starting apparatus comprising, in combination, a motor; means for connecting the motor with a gear of an engine to be started and including a shaft, a pinion movable axially along the shaft into mesh with the engine gear, and provisions whereby the pinion will be automatically demeshed from the engine gear when the engine starts, a pinion shifter movable axially of the shaft; means for effecting rotation of the shifter while it is moved axially; a spring for transmitting axial and rotary movement from the shifter to the pinion whereby the pinion may be rotated in case it abuts the engine gear prior to meshing, said pinion being yieldingly urged by said spring against the engine gear; and means for operating the shifter.

5. Engine starting apparatus comprising, in combination, a motor; means for connecting the motor with a gear of an engine to be started and including a shaft; a pinion movable axially along the shaft into mesh with the engine gear, and provisions whereby the pinion will be automatically demeshed from the engine gear when the engine starts, a pinion shifter movable axially of the shaft; means for effecting rotation of the shifter while it is moved axially; a spring for transmitting axial and rotary movement from the shifter to the pinion whereby the pinion may be rotated in case it abuts the engine gear prior to meshing, said pinion being yieldingly urged by said spring against the engine gear; a manually operable actuator for moving the shifter; and means for automatically disconnecting the actuator from the shifter before the engine starts.

6. Engine starting apparatus comprising, in combination, a motor; means for connecting the motor with the gear of an engine to be started and including a shaft; a pinion movable axially along the shaft into mesh with the engine gear and provisions whereby the pinion will be automatically demeshed from the gear when the engine starts; a pinion shifter movable axially along the shaft and having a connection therewith such that

axial movement of the shifter is accompanied by rotary movement; a spring for transmitting axial and rotary movements from the shifter to the pinion whereby the pinion may be rotated while being yieldingly pressed against the engine gear in case of gear tooth abutment; and means for moving the shifter along the shaft.

7. Engine starting apparatus comprising, in combination, a motor; means for connecting the motor with the gear of an engine to be started and including a shaft; a pinion movable axially along the shaft into mesh with the engine gear and provisions whereby the pinion will be automatically demeshed from the gear when the engine starts; a pinion shifter movable axially along the shaft and having a connection therewith such that axial movement of the shifter is accompanied by rotary movement; a spring for transmitting axial and rotary movements from the shifter to the pinion whereby the pinion may be rotated while being yieldingly pressed against the engine gear in case of gear tooth abutment; a manually operable actuator for moving the shifter; and means for automatically disconnecting the actuator from the shifter before the engine starts.

8. Engine starting apparatus comprising, in combination, a pinion movable axially into mesh with a gear of an engine to be started, a spring for transmitting axial and rotary movements yieldingly to the pinion, and manually operable means for moving the spring axially and rotating it.

9. Engine starting apparatus comprising, in combination, a pinion movable axially into mesh with a gear of an engine to be started, a helical-coil spring co-axial with the pinion and connected therewith to transmit to the pinion axial and rotary movements, manually operable means for moving the spring axially and rotating it.

10. Engine starting apparatus comprising, in combination, a pinion movable axially into mesh with a gear of an engine to be started, a spring for transmitting axial and rotary movements yieldingly to the pinion, a pinion shifter connected with the spring and movable axially of the pinion, means for effecting rotation of the shifter while it is moved axially, and manually operable means for moving the shifter axially.

11. Engine starting apparatus comprising, in combination, a drive shaft, a pinion driven by the shaft and movable axially thereof into mesh with a gear of an engine to be started, a helical-coil spring connected with the pinion for transmitting axial and rotary movements yieldingly thereto, a pinion shifter slidable along the shaft, means so connecting the shifter and shaft that axial movement of the shifter is accompanied by rotary movement, and manually operable means for moving the shifter along the shaft.

12. Engine starting apparatus comprising, in combination, a motor; means for connecting the motor with the gear of an engine to be started and including a pinion movable axially into mesh with the gear of an engine to be started and provisions whereby the pinion will be automatically demeshed from the engine gear when the engine starts; a spring for transmitting axial and rotary movements yieldingly to the pinion; and manually operable means for moving the spring axially and for turning it.

13. Engine starting apparatus comprising, in combination, a motor; means for connecting the motor with the gear of an engine to be started and including a pinion movable axially into mesh with the gear of an engine to be started and provisions whereby the pinion will be automatically demeshed from the engine gear when the engine starts; a spring for transmitting axial and rotary movements yieldingly to the pinion; manually operable means including an actuator for moving the spring axially and for turning it; and means for automatically disconnecting the actuator from the spring before the engine starts.

14. Engine starting apparatus comprising, in combination a motor; a pinion having a lost motion driving connection with the motor and movable axially into mesh with a gear of an engine to be started; a spring for transmitting axial and rotary movements yieldingly to the pinion; and manually operable means for moving the spring axially and for turning it.

15. Engine starting apparatus comprising, in combination a motor; a pinion having a lost motion driving connection with the motor and movable axially into mesh with a gear of an engine to be started; provisions whereby the pinion will be automatically demeshed from the engine gear when the engine starts; a spring for transmitting axial and rotary movements yieldingly to the pinion; and manually operable means for moving the spring axially and for turning it.

16. Engine starting apparatus comprising, in combination a motor; a pinion having a lost motion driving connection with the motor and movable axially into mesh with a gear of an engine to be started; provisions whereby the pinion will be automatically demeshed from the engine gear when the engine starts; a spring for transmitting axial and rotary movements yieldingly to the pinion; manually operable means including an actuator for moving the spring axially and for turning it; and means for automatically disconnecting the actuator from the spring before the engine starts.

17. Engine starting apparatus comprising, in combination, a motor; a helically splined shaft driven thereby; a pinion movable along the shaft into mesh with a gear of an engine to be started and having a lost-motion-drive

connection with said helical splines; a spring for transmitting axial and rotary movements yieldingly to the pinion; manually operable means including an actuator for moving the spring axially and for turning it; and means for automatically disconnecting the actuator from the spring before the engine starts.

18. Engine starting apparatus comprising, in combination, a motor; a helically splined shaft driven thereby; a pinion movable along the shaft into mesh with a gear of an engine to be started and having a lost-motion-drive connection with said helical splines; a spring for transmitting axial and rotary movements yieldingly to the pinion; a pinion shifter connected with the spring and movable along the shaft and so connected therewith that axial movement of the shifter is accompanied by rotation thereof; manually operable means including an actuator for moving the shifter axially; and means for automatically disconnecting the actuator from the shifter before the engine starts.

19. Engine starting apparatus according to claim 18 in which the shifter is a tube surrounding the shaft and has an oblique slot for receiving a pin extending from the shaft.

20. Engine starting apparatus according to claim 18 in which the shifter slides along the shaft and has a slot oblique to the axis of the shaft for receiving a pin extending from the shaft, said slot having a notch normally receiving the pin, and said spring being normally biased for holding the notched portion of the shifter in engagement with the pin and thus yieldingly to prevent movement of the shifter toward the engine gear.

In testimony whereof I hereto affix my signature.

FRANK H. PRESCOTT.
